UNITED STATES PATENT OFFICE.

GEORGE W. STOUT, OF MERCHANTVILLE, NEW JERSEY.

PACKAGE TIE.

1,418,743.

Specification of Letters Patent. Patented June 6, 1922.

Application filed September 4, 1919. Serial No. 321,693.

To all whom it may concern:

Be it known that I, GEORGE W. STOUT, a citizen of the United States, residing in the city of Merchantville and county of Camden, 5 State of New Jersey, have invented a new and useful Package Tie, of which the following is a specification.

My invention consists of a novel construction of a package tie comprising a body portion having an eye therein for the reception of the end of the tying cord, there being an oblique passage extending into the body of the tie from one edge thereof, and a passage from said eye leading to said oblique passage, which latter terminates at about the center of the tie body and is provided with a curved portion which terminates in converging walls, which meet at an angle which co-operates with a recess in the opposite side 20 edge of the tie body, whereby the end of the tying cord after being wrapped around the package or bundle is engaged in such a manner that the package tied can not become untied under any conditions.

For the purpose of illustrating my invention, I have shown in the accompanying drawings, forms thereof which are at present preferred by me, since they will give in practice satisfactory and reliable results. It is to 30 be understood that the various instrumentalities of which my invention consists can be variously arranged and organized and that my invention is not limited to the precise arrangement and organization of these instrumentalities as herein shown and described.

Figure 1 represents a perspective view of a package tie embodying my invention, showing the manner of manipulating and tying the tying cord.

Figure 2 represents a section on line 2—2 Figure 1.

Figure 3 represents a plan view of the package tie body in detached position.

Similar numerals of reference indicate 45 corresponding parts in the figures.

Referring to the drawings:—

1 designates my novel construction of a package tie, the same being provided with the ends or end edges 2, and the sides or side 50 edges 3 and 4, and being composed of vulcanized fibre, thin sheet metal, or the like.

5 designates an oblique slot which enters the edge 3 and terminates about the middle of the tie body in the recess 6, a portion of

which is arc shaped and provided with walls 7 and 8 which meet at the point or apex 9.

10 designates an eye formed on about the longitudinal median line of the tie body, towards the end 2 thereof from which eye extends the slot or passage 11, which meets or 60 merges into the oblique slot or passage 5. The edge 4 of the body 2 has a recess 12 therein, which is located about midway of the holes 6 and 10.

13 designates a tying cord, which has a 65 knot 14 in its end, said knot being covered with cement or the like as 15, whereby its life is indefinitely prolonged.

16 designates the package, or bundle, as newspapers or the like to be tied. In the 70 tying operation, the package or bundle, as tied, is seen in Figure 1, the tying cord 12 after being wrapped around the bundle 15 as indicated in said figure has its extremity 17 after being passed through the central opening 6, pulled and passed around the recess 12 and then passed under the end 2, thence through the slot 5, and a pull being exerted thereupon, said end 17 will then engage the apex of the triangle formed by the converging walls 7 and 8 whereby the package will 80 be firmly tied, and the end 17 positively prevented from disengagement therefrom. A pull on the end 17 in the proper direction reverse to the tying operation will untie the 85 cord.

It will now be apparent that I have devised a novel and useful package tie, which embodies the features of advantage enumerated as desirable in the statement of the invention and the above description, and while I have, in the present instance, shown and described preferred embodiments thereof which will give in practice satisfactory and reliable results, it is to be understood that 95 the same are susceptible of modification in various particulars without departing from the spirit or scope of the invention or sacrificing any of its advantages within the scope of the appended claim.

Having thus described my invention, what I claim as new and desire to secure by Letters Patent, is:—

A package tie, comprising a tie body having an oblique slot entering one edge thereof 105 and terminating near the middle of said body in converging walls which extend at an angle to said slot and meet at the apex 9 lo-

cated out of alignment with said slot, and an inclined passage 11 with converging side walls merging into said slot and terminating in an eye located substantially on the median line of said body, the diameter of said eye being greater than the width of said passage at its terminal and the edge of said

body opposite to said oblique slot having a recess therein located intermediately of said apex and eye.

GEORGE W. STOUT.
